Filed Feb. 12, 1974, Ser. No. 441,862

Term of patent 14 years

Int. Cl. D7—05

U.S. Cl. D7—179

FIG. 1 is a perspective view of a firearm chamber lubricating and cleaning device showing my new design;

FIG. 2 is a side elevational view thereof;

FIG. 3 is a plan view thereof;

FIG. 4 is a rear elevational view thereof; and

FIG. 5 is an end elevational view thereof.

The cross-hatched representation of a surface pattern which is shown on the handle in FIGS. 1, 2, 3 and 4 is understood to repeat throughout the indicated area.

I claim:

The ornamental design for a firearm chamber lubricating and cleaning device, as shown and described.
